THOMAS F. BRAZEIL, OF NEW BEDFORD, MASSACHUSETTS, ASSIGNOR TO DRAPER COMPANY, OF HOPEDALE, MASSACHUSETTS, A CORPORATION OF MAINE.

PROTECTING-TIP FOR DROP-WIRE-BAR ENDS.

1,144,686.

Specification of Letters Patent. Patented June 29, 1915.

Application filed May 16, 1914. Serial No. 839,151.

To all whom it may concern:

Be it known that I, THOMAS F. BRAZEIL, a citizen of the United States, residing at New Bedford, county of Bristol, State of Massachusetts, have invented an Improvement in Protecting-Tips for Drop-Wire-Bar Ends, of which the following description, in connection with the accompanying drawing, is a specification, like characters on the drawing 10 representing like parts.

This invention relates to means for facilitating the assembling of drop wires upon the drop wire bars of looms, and for protecting said drop wires from injury as they are 15 hurriedly thrust over the recessed ends of said bars.

As is well known in the art each warp end 20 of the loom normally supports a drop wire which when the warp end breaks falls into the path of the vibrating or reciprocating feeler which being arrested thereby initiates the action of suitable stop mechanism for the loom.

The drop wires are slotted near their upper 25 ends and supported upon a suitable drop wire bar which is ordinarily provided at one end with a longitudinal slot and at the opposite end with a transverse slot or recess, said slots being adapted to receive suitable 30 screw threaded pins or bolts extending from brackets carried by the loom frame, the pins being provided with thumb nuts to clamp the drop wire bars upon a supporting bracket.

In order to assemble the drop wires on the 35 bar the thumb nuts are loosened and the bar pivotally moved about the pin which enters the longitudinal slot until the transverse slot in the opposite end is disengaged from its 40 pin, whereupon the drop wires are thrust over the other end of the bar. In sliding the drop wires upon the bar they frequently engage the edges of the walls of the recess or the sharp edges of the end of the bar and in 45 being forced over the same become bent or injured so that they do not perform their functions properly.

One object of the present invention is to provide means for preventing such engage-

ment and thereby to prevent injury to the 50 drop wires.

Another object of the invention is to provide a tapered protecting and guiding means for the recessed end of the drop wire bar adapted to enter readily into the slots in the 55 drop wires whereby the latter may be assembled upon the bar without the necessity of carefully positioning the drop wires as they are passed over the end of said bar.

Other objects of the invention and the nature thereof will more fully appear from the following description and the accompanying drawings and will be particularly pointed out in the annexed claims.

In the drawings: Figure 1 is an elevation 65 of the drop wire bar and a few of the drop wires of a loom, illustrating the manner in which the same are supported in the loom, the central portion of the illustration being broken away, Fig. 2 is a detail elevation of a 70 drop wire showing the manner in which it is mounted upon the drop wire bar, Fig. 3 is a detail side elevation of one of the recessed ends of a drop wire bar with the 75 guiding and protecting device applied thereto, Fig. 4 is a perspective view of the guiding and protecting tip.

The warp stop motion mechanism for 80 looms is usually supported, as shown in Fig. 1, upon arms 1, extending upwardly and inwardly from the side frames of the loom, said arms being provided at their upper ends with laterally bent portions 2 to which brackets 3 are attached, said brackets being provided with upwardly projecting stands 85 4, having upstanding flanges 5 provided with screw threaded pins or bolts 6 adapted to receive the slotted ends of a drop wire bar 7 which are securely clamped against said flanges 5, preferably by thumb nuts 8. 90

The brackets 3 have downward extensions 9 provided with bosses 10 at their lower ends in which the feeler shaft 11 is suitably mounted. The usual stop motion girts 12 are secured in any suitable manner as by 95 screws or bolts 13 to the sides of the depending arms 9 of said bracket.

The feeler mechanism may be of any usual

character and is not illustrated herein as it forms no part of the present invention.

The drop wire bar 7 is usually provided at one end with a longitudinal slot 14 adapted to be slipped over the pin 6 while the opposite end of this bar is desirably provided with a transverse recess or slot 15 adapted to engage the pin 6 which extends from the flange 5 at the opposite end of the loom.

10 The drop wires 16 are of the usual form having slots 17 adjacent their upper ends and circular apertures 18 approximately at their middle through which the warp ends are threaded, the lower ends of the drop wires 15 being adapted upon the breaking of the warp end to fall into the path of the vibrating feeler and to thereby initiate the action of the stop mechanism of the loom in the usual manner.

20 In order to assemble the drop wires upon the drop wire bar 7 said bar is removed, or is pivotally moved about one of the supporting rods 6 whereupon the drop wires are slipped over the end of the bar.

25 The ends of the drop wire bar usually have relatively sharp edges and the recesses or slots adjacent to the ends are usually formed by punching so that there are sharp or ragged edges about the walls of 30 such recesses. If in slipping the drop wires over the ends of the drop wire bar the operator is not careful he is likely to cause the narrow sides of the drop wires to engage the sharp edges of said ends, or the walls of the 35 recess, and by forcing the drop wire there-over to distort, crack or break the drop wire so that it will not perform its function in the loom properly.

The present invention comprises broadly 40 the providing of means for covering or inclosing the ends of the drop wire bars and recess therein, or both, in such a manner as to prevent engagement of the drop wires with the sharp edges thereof, it also comprehends a guiding means whereby the drop 45 wires may be more quickly assembled upon the drop wire bar than in the ordinary manner.

In the preferred form of invention illustrated herein this means comprises a hollow 50 tapered tip 20 as illustrated in Figs. 3 and 4, the body portion 21 being hollow and substantially rectangular in form to pass over and fit the end of the drop wire bar and to 55 inclose the slot 15 therein, so that the drop wires cannot engage the end, enter the slot, or engage the walls thereof.

The outer end of the tip 20 is desirably 60 provided with converging edges 22, 23 and the sides of the point of the tip are also desirably made converging so that the extremity 24 is relatively small.

When the drop wires are to be assembled upon the drop wire bars the removable tip

20 is placed upon the end of the bar, covering 65 up the transverse slot or recess and the drop wires rapidly passed over the same.

It will be obvious that the drop wires can be much more easily positioned upon the beveled tip than upon the square end of the 70 drop wire bar and considerable time is thereby saved in assembling thereon the large numbers of drop wires necessary for 75 each loom. It will also be observed that the protecting tip prevents the engagement of the drop wires with any sharp edge or with the walls of the recess so that they will not be likely to become distorted or broken in being slipped onto the drop wire bar.

While the device illustrated herein is the 80 preferred form of the invention it will be obvious that it may be made in various other forms and my invention comprehends any form whereby the drop wire may be guided upon the drop wire bar and any means by 85 which it may be prevented from engaging the sharp edges of the ends of the bar or the walls of the slot or recess in said end.

Having thus described my invention what I claim as new and desire to secure by Letters Patent is:

1. In combination with warp stop mechanism for looms comprising a drop wire bar having a recessed end by means of which it is detachably supported in the loom, a removable guiding member adapted to cover said recess to prevent engagement of the drop wires therewith when being assembled upon said bar.

2. In combination with warp stop mechanism for looms comprising a drop wire bar having a recessed end by means of which it is supported in the loom, a hollow removable guiding member adapted to inclose the end of said bar and to cover the walls of 105 said recess whereby injury to the drop wires will be prevented as the same are being assembled upon the drop wire bar.

3. A removable guide tip for the drop wire bar of a loom comprising a member 110 having a tapered end and a hollow base adapted to inclose the recessed end of the bar to prevent injury to the drop wires when being assembled thereon.

4. A removable guide tip for the drop wire bar of a loom comprising a metallic member having a flat tapered end portion and a hollow base and adapted to inclose and cover the recessed end of the bar to prevent injury to the drop wires when being 120 assembled thereon.

5. In combination with warp stop mechanism for looms comprising a drop wire bar having a recessed end by means of which it is supported in the loom; a removable guiding member for the drop wires consisting of a tip having a rectangular hollow body portion adapted to fit the end por-

tion of the drop wire and to inclose and cover the walls of the recess therein, and a flat tapered portion extending from said body portion and presenting a narrow end 5 adapted to enter the slots in the drop wires to facilitate assembling the same upon the drop wire bar.

In testimony whereof, I have signed my name to this specification in the presence of two subscribing witnesses.

THOMAS F. BRAZEIL.
